UNITED STATES PATENT OFFICE

2,644,359

SOCKET WRENCH HAVING SWIVELED
GRIP SLEEVEJohn E. Lytle, Akron, Ohio, assignor to The Ken-
Tool Manufacturing Company, Akron, Ohio, a
partnership

Application July 8, 1948, Serial No. 37,630

2 Claims. (Cl. 81—177)

1

This invention relates to socket wrenches and in particular relates to the four-armed type of socket wrenches.

Heretofore, integral four-armed socket wrenches have been provided which had sockets of different sizes on the free ends of the arms thereof adapted to be selectively engaged with a nut on a bolt or similar work to remove or apply the same, as by spinning the wrench about the axis of the arm of the socket engaging the nut. Such wrenches, however, would not spin readily, and in wet weather or similar conditions would not spin at all, due to friction of the operator's hand used, while wet, as a bearing for the wrench as it was spun.

One object of the present invention is to provide a four-armed wrench of the character described, including improved means for permitting effective spinning of the tool under all conditions of weather and conditions of the hands of the operator using the tool.

Another object of the invention is to provide a tool of the character described having the advantages referred to above, and yet which will be extremely economical to produce and will have no parts to get out of order, lost or misplaced.

Other objects of the invention will be manifest from the following brief description and the accompanying drawing.

Of the accompanying drawing:

Figure 1 is a top plan view of a socket wrench embodying the features of the invention.

Figure 2 is an enlarged fragmentary view of one of the arms of the wrench, the same being partly broken away and in section.

Referring to the drawing the numeral 10 designates generally a socket wrench comprising cross members 11 and 12 integrally forged together at the center of the tool to provide four arms 13, 14, 15 and 16 extending at right angles to each other, or in the form of a cross. These arms have integrally formed on the free ends thereof wrench sockets 17, 18, 19 and 20 of different sizes, for receiving nuts or bolt heads of corresponding sizes.

Each of the arms 13 to 16 has a straight cylindrical portion 24 about which is rotatably received a tubular sleeve 25 of metal or other suitable material, the opposite ends of the sleeve being crimped, at 26, 26 over spaced annular rib portions 27 integrally formed in the respective arm, thereby to prevent movement of the sleeve longitudinally of the arm and yet permitting rotation of the sleeve with respect thereto. The

2

crimped portions 26 also provide maximum protection against the operator getting his hand pinched between the ends of the sleeve and the rib portions 27.

5 The sleeves 25 may be readily applied to the arms 13 to 16 as by applying partially formed, split sleeves over the straight portions 24 of the arms and closing the partially formed sleeves to cylindrical shape about said straight portions.

10 For providing non-slip engagement of the hand with the sleeves 25 they may have formed or impressed on the outer surfaces thereof a plurality of closely spaced projections 28.

15 In operation or use of the tool, as for removing a nut 30 from a bolt 31 of a vehicle wheel, the socket 20 of corresponding size is applied to the nut, whereby the operator after loosening the nut in the usual way may be grasping the sleeve 25 of the arm 14 engage one of the angularly extending arms 13 or 15 and cause the wrench to spin or turn about the axis through the aligned arms 16 and 14. The wrench may be similarly engaged and spun in applying a nut to a bolt. The oppositely extending arms 13 and 15 provide balance for free spinning action of the wrench.

20 Thus has been provided an improved four-armed socket wrench which overcomes the fore-mentioned defects of the ordinary type of four-armed wrench, and yet which is simple in construction and economical to manufacture. There are no parts to become loose or detached from the wrench, or to get out of order.

25 Modifications of the invention may be resorted to without departing from the spirit thereof or the scope of the appended claims.

What is claimed is:

30 1. A cross-membered tool comprising a hub and four arms extending substantially at right angles to each other from the hub, said arms having work-engaging heads on the free ends thereof, operable on the work by turning the tool on the axis of respectively opposite arms, an elongated sleeve relatively rotatably mounted on each of said arms, each of said sleeves being of sufficient length to be non-rotatively gripped in the hand while the tool is rotated with the turning head of the opposite arm operatively engaged with the work, said sleeved cross-members having spaced annular ribs thereon and said sleeve having opposite end portions thereof rotatably crimped over said ribs to prevent longitudinal movement of the sleeve on its cross-member.

35 2. A cross-membered tool comprising a hub

and four rigidly connected arms extending at right angles to each other generally in a plane from said hub, said arms having wrench sockets or like work-engaging tool heads on the free ends thereof, operable on the work by turning the tool on the axis of respectively opposite arms, elongated sleeves relatively rotatably mounted on each of said arms, said tool thereby being adapted to be rotated about an axis of one cross-member while the tool head of an arm thereof presented outwardly of an operator of the tool is engaged with work to be turned and while said operator grips against rotation the sleeve on the correspondingly inwardly presented arm of said one cross-member to steady the rotated tool, said arms each having thereon spaced annular ribs and the respective sleeves thereof having opposite end portions of the same crimped

over said spaced ribs to prevent relative longitudinal movement of the sleeves.

JOHN E. LYDLE.
